UNITED STATES PATENT OFFICE.

BLAIR L. MOHNEY, OF MCKEESPORT, PENNSYLVANIA.

CLOTHES-RACK.

1,046,319.

Specification of Letters Patent.

Patented Dec. 3, 1912.

Application filed February 27, 1911. Serial No. 611,190.

To all whom it may concern:

Be it known that I, BLAIR L. MOHNEY, a citizen of the United States of America, residing at McKeesport, in the county of 5 Allegheny and State of Pennsylvania, have invented certain new and useful Improvements in Clothes-Racks, of which the following is a specification, reference being had therein to the accompanying drawing.

10 This invention relates to clothes racks, and the primary object of the invention is to provide a rack that can be folded to occupy a comparatively small space when not in use.

15 Another object of the invention is to provide a rack that can be advantageously used in proximity to a stove for holding clothes over the stove, whereby they will be quickly dried, the rack being constructed whereby it 20 can be secured to a wall or other support and easily placed in an operatable condition.

A further object of the invention is to provide a rack that is simple in construction, durable, easy to manipulate and highly efficient for the purposes for which it is intended.

With the above and other objects in view, the invention resides in the novel construction, combination and arrangement of parts 30 to be hereinafter specifically described and then particularly claimed.

Reference will now be had to the drawing, wherein like numerals of reference designate corresponding parts throughout the 35 several views, in which:—

Figure 1 is a perspective view of the rack. Fig. 2 is a front elevation of a portion of a the same. Fig. 3 is a rear elevation of a portion of the rack, and Fig. 4 is a horizontal sectional view of the same.

40 A rack in accordance with this invention comprises a back plate 1 provided with openings 2 whereby said plate can be secured to a wall or other support by nails or other fastening means.

45 The front side of the plate 1 is provided with two outwardly extending semi-circular plates 3 arranged in parallelism, and these plates are spaced apart by equally spaced 50 tapering blocks 4, said blocks providing equally spaced tapering sockets 5. The blocks 4 and the plates 3 can be suitably secured together by glue, nails or other fastening means.

Arranged in front of the blocks 4 is a 55 semi-circular support 8, preferably made of wire, said support having the ends thereof bent inwardly, as at 9, hook-shaped as at 10, and secured to the rear side of the plate 1 by staples or other fastening means 11, 60 said plate being recessed, as at 12 to provide clearance for the ends of the support 8, thereby allowing the plate 1 to rest evenly against the wall or other support.

Movably mounted upon the support 8 are 65 a plurality of arms 13, said arms having the upper ends thereof longitudinally slotted, as at 14 to receive the support 8, and the upper ends of the arms are tapered, as at 15 to fit in the sockets 5 and support the arms at 70 right angles and radially disposed relatively to the back plate 1. The slots 14 are of sufficient length to permit of the arms being pulled outwardly and swung to a vertical position, as shown in Fig. 1 of the 75 drawing, thereby occupying a comparatively small space when not in use.

The rack, with the exception of the support 8, is preferably made of wood, and can 80 be made of various sizes.

What I claim is:—

A clothes rack comprising a supporting plate having its rear face formed with a pair of oppositely disposed L-shaped grooves, a pair of forwardly-projecting parallel semi-circular members carried by the plate intermediate the upper and lower ends thereof, radially disposed spaced tapering blocks interposed between said members and providing a row of tapering sockets, a semi-circular support arranged forwardly of and centrally with respect to said sockets, said support spaced from said sockets, having inwardly-extending L-shaped ends arranged 85 in said grooves, means within the grooves for securing the ends of said support to said plate, and arms having slots in proximity to their inner ends, said support extending through said slots, and further having the inner ends tapered and fitted in said sockets. 90

100 In testimony whereof I affix my signature in the presence of two witnesses.

BLAIR L. MOHNEY.
